UNITED STATES PATENT OFFICE.

FREDERICK GRINNELL, OF NEW BEDFORD, MASSACHUSETTS, ASSIGNOR
TO GENERAL FIRE EXTINGUISHER COMPANY, OF NEW YORK, N. Y.,
A CORPORATION OF NEW YORK.

DRY-PIPE VALVE.

SPECIFICATION forming part of Letters Patent No. 761,165, dated May 31, 1904.

Application filed September 11, 1902. Serial No. 122,985. (No model.)

To all whom it may concern:

Be it known that I, FREDERICK GRINNELL, of New Bedford, in the county of Bristol and State of Massachusetts, have invented certain new and useful Improvements in Dry-Pipe Valves; and I do hereby declare the following specification, taken in connection with the accompanying drawings, forming a part of the same, to be a full, clear, and exact description thereof.

The invention relates to dry-pipe valves for automatic sprinkler systems, in which a water-valve is held closed against the water-pressure in the supply-pipe by means of a lighter pressure of air or other fluid in the distributing-pipes.

The object of the present invention is to provide an arrangement whereby when the water-valve is opened it will be removed from the waterway and so that there will be a free and unobstructed passage for the water through the valve-casing.

To that end the invention consists in the combination and arrangement of parts hereinafter described and claimed.

Referring to the drawings, Figure 1 is a vertical section of a dry-pipe valve embodying my invention. Fig. 2 is a vertical section on the line $\alpha\alpha$, Fig. 1.

A represents the valve-casing, adapted to be connected at one end, a , with the water-supply pipe and at the other end, a' , with the delivery-pipe leading to the sprinkler system.

B is a double-seated valve adapted to seat on one side against the fixed valve-seat b and on the other side against the valve-seat c , formed on the movable member C. The movable member C is connected to the valve-casing by a yielding connection c' , which may be formed of thin metal, such as brass.

In the construction shown the inner edge of the yielding connection c' is secured to the movable member C, and its outer edge is clamped between the two parts of the valve-casing, the construction being such as to permit the movement of the member C and the valve-seat carried thereby. The space between the fixed valve-seat b and the movable member

constitutes the intermediate chamber, which is normally open to the atmosphere through a drip-pipe d in the usual manner.

The valve-casing A is arranged so that the waterway therethrough extends in a horizontal direction, and said casing is provided on its lower side with an extension or enlargement to form a chamber or pocket E of suitable size to receive the valve B.

With the construction and arrangement of parts above described, where the valve B is set in position to close the waterway and the requisite pressure is produced in the distributing-pipes, the valve will be clamped between the fixed valve-seat and the movable valve-seat and will be held in that position by the pressure in the system acting upon the movable member C. When now the pressure in the system is reduced, as by the opening of a sprinkler, the valve will be unclamped and will be free to fall into the chamber E, where it will be removed from the waterway and so as to leave a free and unobstructed passage through the valve-casing.

Means may be provided for limiting the movement of the valve B in opening and for guiding the valve in its movement out of the waterway, and such means are shown in the drawings, the same consisting of the projections $b^2 b^2$, formed on opposite sides of the valve and adapted to engage corresponding projections $a^2 a^2$, formed on the inside of the valve-casing. The projections $a^2 a^2$ are preferably extended to the bottom of the chamber E, as shown in Fig. 1. As will be readily understood, said projections $a^2 a^2$ will serve to limit the extent to which the valve will move with the movable member in opening and will also serve to guide the valve in its movement out of the waterway.

If desired, a flexible folding connection may be substituted for the yielding connection c' of such character as to provide for a greater range of movement of the movable member, if this should be found desirable. In such case the valve-casing would of course be formed so as to permit such increased movement of the movable member.

The valve-casing is provided with a large opening, closed by a cover-plate A', by the removal of which access may be had to the valve for the purpose of cleaning or reseating the 5 same.

In addition to providing a free and unobstructed passage for the water through the valve-casing the removal of the valve from its position in the waterway also furnishes an 10 effective means for preventing columning of the valve after it has been once opened. With the valve thus removed from position it cannot, of course, become accidentally reseated or columned.

15 What I claim as my invention, and desire to secure by Letters Patent, is—

1. In a dry-pipe valve, the combination of a valve, a fixed seat for said valve and a movable seat for said valve between which fixed 20 and movable seats the valve is clamped and held in position to close the waterway as long as the requisite pressure is maintained in the system, said valve being free to fall out of the waterway when the pressure in the system 25 is reduced, substantially as described.

2. In a dry-pipe valve, the combination, with the valve-casing, of a valve, a fixed seat for said valve and a movable seat for said valve, between which fixed and movable seats the 30 valve is clamped and held in position to close the waterway as long as the requisite pressure in the system is maintained, said valve being free to fall out of the waterway when the pressure in the system is reduced, and said valve-casing being provided with a chamber to receive said valve, substantially as described.

3. In a dry-pipe valve, the combination of a valve, a fixed seat for said valve, a movable member subjected to the pressure in the system, a valve-seat carried by said movable member, between which fixed and movable seats 35

the valve is clamped and held in position to close the waterway as long as the requisite pressure is maintained in the system, said valve being released and free to fall out of the waterway when the pressure in the system is reduced, substantially as described. 45

4. In a dry-pipe valve, the combination of a valve, a fixed seat for said valve, a movable member subjected to the pressure in the system, a valve-seat carried by said movable member, between which fixed and movable seats the valve is clamped as long as the requisite pressure is maintained in the system, said valve being free to fall out of the waterway when the pressure in the system is reduced, and means for arresting the movement of the valve in opening before the movable member has reached the limit of its movement, substantially as described. 50

5. In a dry-pipe valve, the combination of a valve, a fixed seat for said valve, a movable seat for said valve, between which seats the valve is normally clamped and held in position to close the waterway, said valve being free to fall out of the waterway when released, and means to guide said valve in its falling movement, substantially as described. 55

6. In a dry-pipe valve, the combination of a valve, a fixed seat for said valve, a movable seat for said valve, between which seats the valve is normally clamped and held in position to close the waterway, said valve being free to fall out of the waterway when released, means to limit the movement of said valve in opening, 70 and means to guide said valve in its falling movement, substantially as described. 75

FREDERICK GRINNELL.
